UNITED STATES PATENT OFFICE.

SIVERT B. NILSEN, OF WARROAD, MINNESOTA.

HINGE.

1,045,875.

Specification of Letters Patent.

Patented Dec. 3, 1912.

Application filed June 22, 1912. Serial No. 705,192.

To all whom it may concern:

Be it known that I, SIVERT B. NILSEN, a citizen of the United States, residing at Warroad, in the county of Roseau and State 5 of Minnesota, have invented certain new and useful Improvements in Hinges; and I do hereby declare the following to be a full, clear, and exact description of the invention, such as will enable others skilled 10 in the art to which it appertains to make and use the same.

My invention has for its object to provide an improved hinge especially designed as an improvement on that class of hinges 15 disclosed and claimed in my prior United States Patent No. 685,218, issued to me of date October 22, 1901, entitled "Hinge".

To the above end, the invention consists of the novel devices and combinations of devices hereinafter described and defined in 20 the claims.

The invention is illustrated in the accompanying drawings, wherein like characters indicate like parts throughout the several 25 views.

Referring to the drawings.—Figure 1 is an end elevation of the improved hinge, secured in working position to a portion of a door and door casing, shown in transverse 30 section, taken on the line $x^1 x^1$ of Fig. 2; Fig. 2 is a front elevation of the parts shown in Fig. 1; and Fig. 3 is a transverse section taken on the line $x^2 x^2$ of Fig. 2.

The numeral 1 indicates a door attached to 35 a door casing 2 by the improved hinge, and the numeral 3 indicates the door jamb.

The numerals 4 and 5 indicate the two leaves of the improved hinge. At its inner edge, the hinge leaf 4 is provided with a 40 laterally out turned extension 6 which terminates at its free edge in a pair of alined hinge knuckles 7. Partially cut and bent from the intermediate portion of the hinge leaf 4 and its extension 6, is a brace arm 8 rigidly secured, at its free end to the said 45 hinge leaf 4, by a wood screw 9 passed through alined holes in the brace arm 8 and hinge leaf 4 and screwed into the door 1. As shown, the hinge leaf 4 is further secured 50 to the door 1 by means of a multiplicity of wood screws 10 passed through holes formed in the hinge leaf 4.

At its inner edge, the hinge leaf 5 terminates in a pair of hinge knuckles 11 that 55 embrace the hinge knuckles 7 and are alined therewith. A pintle 12 is passed through

the alined hinge knuckles 7 and 11 and connects the leaves 4 and 5 for hinge-like movement. The pintle 12 is also adjustably secured to one of the hinge knuckles 11 and 60 held against rotation with respect thereto, by means of a pin or lug 13 on the pintle 12 and is arranged to be seated in any one of a multiplicity of notches 14 formed in the hinge knuckles 11. Telescoped onto the 65 pintle 12, between the hinge knuckles 7, is a spiral torsional spring 15. This spring is anchored at one end to a disk 16 rigidly secured on the pintle 12, and, at its other end, is anchored to one of the hinge knuckles 70 7. As is evident, the tension of the spring 15 may be varied by adjusting the pintle 12 with respect to the hinge knuckle 11 to which it is connected by the pin 13 and notches 14. 75

Integrally formed with each edge portion of the hinge leaf 5 and extending outward at right angles therefrom, is a hinge knuckle 17. Pivotal secured to these hinge knuckles 17, is an adjustable supplemental base section 18 in the form of a flat plate secured to the door casing 2 by means of wood screws 19 passed through holes formed in the supplemental base section 18. Each end of the base section 18 terminates in an out turned 85 hinge knuckle 20. These hinge knuckles 20 embrace the hinge knuckles 17 and are pivotally secured thereto by means of rivets 21. 80

The outer edge portion of the hinge leaf 5 terminates in a curved outer portion 22 that 90 is concentric to the rivets 21 and its under surface portion works in close engagement with the outer face of the base section 18, as best shown in Fig. 3. Formed in the base plate 18, is a pair of elongated slots 23 that are 95 alined with the rivets 21, as shown in Fig. 2. Intersecting the elongated slots 23, is a pair of segmental slots 24 formed in the curved outer portion 22 of the hinge leaf 5. Passed through the pairs of slots 23 and 24, at their 100 points of intersection, is a pair of wood screws 25 that have screw threaded engagement with the door casing 2.

To apply the improved hinge in working position, the hinge leaf 4 is first secured, by the wood screws 10, to the door 1. Next, the supplemental base section 18 is pressed into flat engagement with the door casing 2 and then forced toward the door 1 as far as the hinge leaf 5 will permit. In this position, the supplemental base section 18 is secured to the door casing 2 by means of the 105 110

wood screws 19. After the supplemental base section 18 is rigidly secured in position, the wood screws 25 are passed through the two pairs of slots 23 and 24, at their points of intersection, and screwed into the door casing 2. By forcing the heads of the wood screws 25 against the curved outer portions 22, of the hinge leaf 5, said curved outer portion 22 is frictionally clamped onto the upper face of the supplemental base section 18, and thereby rigidly held against pivotal movement on the rivets 21. The segmental slots 24 are arranged so as to extend transversely of the direction of movement of the hinge leaf 5 with respect to the supplemental base section 18 and the screws 25 passed therethrough securely hold the hinge leaf 5 from working loose during the opening and closing movement of the door 1.

20 As is evident, if desired, the improved hinge may be secured in working position in a reverse order from that shown in the drawings. It is also evident that the improved hinge may be constructed from cast metal 25 instead of pressed metal as shown in the accompanying drawings.

The above described hinge, while extremely simple and of comparatively small cost to manufacture, is thought to be highly efficient for the purpose had in view.

What I claim is:—

1. A hinge comprising a pair of pivotally connected leaves, one of which is secured to a support by laterally off-set pivotally connected knuckles and provided with a curved portion concentric to the pivotal connection of said knuckles, and means for securing said curved portion with respect to said support, substantially as described.

40 2. A hinge comprising a pair of pivotally connected leaves, one of which is secured to a support by laterally off-set pivotally connected knuckles and provided with a curved portion concentric to the pivotal connection of said knuckles, a segmental slot formed in said curved portion, and anchoring means passed through said slot and secured to said support, substantially as described.

50 3. A hinge comprising a pair of pivotally connected leaves, one of which is provided with an adjustable supplemental base section, and common means for rigidly securing said supplemental base section and

the hinge leaf to which it is connected to a common support.

4. A hinge comprising a pair of pivotally connected leaves off-set with respect to each other, one of said leaves having an adjustable supplemental base section connected thereto by pivotally connected off-set hinge knuckles, and a curved outer portion concentrically located with respect to the pivotal connection of said hinge knuckles and working over said base section, said base section 65 and curved outer portion of said hinge leaf having intersecting slots, and anchoring means insertible through said intersecting slots and into a suitable support for securing said base section and connected hinge 70 leaf with respect to each other and to said support, substantially as described.

5. A hinge comprising a pair of pivotally connected leaves off-set with respect to each other, one of said leaves having an adjustable supplemental base section connected thereto by pivotally connected off-set hinge knuckles, and a curved outer portion concentrically located with respect to the pivotal connection of said hinge knuckles and 80 working over said base section, said base section having an elongated slot alined with the pivotal connection of its hinge knuckles, and a segmental slot in the curved outer portion of said hinge leaf and intersecting said elongated slot, and anchoring means insertible through said intersecting slots and into a suitable support for securing said base section and connected leaf hinge with respect to each other and to said support, 85 substantially as described.

6. A hinge comprising a pair of leaves stamped from sheet metal, one of said leaves being provided with a lateral extension terminating in hinge lugs to which the other 95 of said leaves is pivotally secured, a brace arm partly cut and pressed from said lateral extension and the connected hinge leaf, and common anchoring means for securing the free end of said brace arm to the connected hinge leaf and to a support, substantially as described.

In testimony whereof I affix my signature in presence of two witnesses.

SIVERT B. NILSEN.
